UNITED STATES PATENT OFFICE.

EGBERT G. JACKSON, OF WHITAKER, PENNSYLVANIA.

GAME APPARATUS.

1,176,367.

Specification of Letters Patent. Patented Mar. 21, 1916.

Application filed September 18, 1915. Serial No. 51,387.

To all whom it may concern:

Be it known that I, EGBERT G. JACKSON, a citizen of the United States, residing at Whitaker, in the county of Allegheny and State of Pennsylvania, have invented certain new and useful Improvements in Game Apparatus, of which the following is a specification, reference being had to the accompanying drawings.

10 This invention relates to certain improvements in game apparatus and has relation more particularly to a device of this general character wherein surface projectiles are employed; and it is an object of the invention 15 to provide a novel and improved device of this general character wherein skill in employing the same is required and whereby a maximum of amusement is afforded.

The invention consists in the details of 20 construction and in the combination and arrangement of the several parts of my improved game apparatus whereby certain important advantages are attained and the device is rendered simpler, less expensive and 25 otherwise more convenient and advantageous for use, all as will be hereinafter more fully set forth.

The novel features of the invention will be carefully defined in the appended claims. 30 In order that my invention may be the better understood, I will now proceed to describe the same with reference to the accompanying drawings, wherein—

Figure 1 is a view in top plan of the device 35 as herein embodied; Fig. 2 is a sectional view taken substantially on the line 2—2 of Fig. 1; and Fig. 3 is a view illustrating the projectiles herein employed.

As disclosed in the accompanying drawings, 40 1 denotes a base of predetermined dimensions and preferably rectangular in form and having its margins defined by an upstanding flange 2 and the opposite end portions of the base are provided with the inwardly disposed raised portions 3 substantially semi-circular in form and provided at the transverse center of the base 1 with the longitudinally disposed grooves 4. The inner extremity of each of said grooves 4 is 45 provided with the projector mechanism P of any ordinary or preferred construction but preferably comprising the spring controlled plunger 5.

Disposed concentrically with the inner end 50 of each of the raised portions 3 are the ribs 6 and 7, the inner ribs 6 being of a length

less than the ribs 7 and terminating inwardly thereof and the adjacent extremities of the ribs 7 are spaced apart sufficiently to permit an unobstructed travel of a projectile 8 impelled by the projector mechanism P from within the groove 4 so that the same may be caused to strike the upstanding peg 9 positioned concentrically of the raised portions 3. The side marginal portions of the base 1 are provided with the inwardly disposed raised portions 10, the sides of which being disposed concentric to the opposed sides of the adjacent ribs 7 and said raised portions 10 are of a length less than the length of the ribs 7. It is preferred that the raised portions 10 be substantially V-shape in plan. It is also to be observed that the free or inner extremities of the ribs 6 and 7 are pointed so that no material obstruction will be afforded to the entrance of a projectile 8 within the run-ways R afforded between the ribs 6 and the raised portions 3, the ribs 6 and 7 and the ribs 7 and raised portions 10.

Each of the run-ways R is provided with the depressions 11 provided with the valuations 12 and in playing the game, it is intended that each player have a set of five projectiles 8, said sets being differently colored for the purpose of identity and the projectiles of each set are provided with differing valuations 12 preferably two and a multiple of two. The projectiles 8 are also preferably spherical.

As a projectile 8 is discharged from a groove 4, its course of travel will be deflected by the peg 9 and will have a tendency to enter within one of the run-ways R and should said projectile seat itself within a depression 11 the player will make a score equal to the sum of the valuation 14 of the projectile and the valuation 12 of the depression in which it is seated. It will be understood however that other rules for governing the score may be created if desired.

From the foregoing description, it is thought to be obvious that a game apparatus constructed in accordance with my invention is of an extremely simple and comparatively inexpensive nature and is particularly well adapted for use by reason of the facility with which it may be played and the amusement afforded, and it will also be obvious that my invention is susceptible of some change and modification without material departure from the principles and spirit

thereof and for this reason I do not wish to be understood as limiting myself to the precise arrangement and formation of the several parts herein shown in carrying out my invention in practice.

I claim:

1. A game apparatus comprising a base board having a plurality of run-ways along opposite sides thereof and having a discharging groove at opposite ends arranged in alinement, and an upstanding peg carried by the base board concentrically of the discharging grooves.
2. A game apparatus comprising a base board having a plurality of run-ways along opposite sides thereof and having a discharging groove at opposite ends arranged in alinement, and an upstanding peg carried by the base board concentrically of the discharging grooves, the run-ways terminating at opposite sides of the plane occupied by the discharging grooves.
3. A game apparatus comprising a base board having a plurality of run-ways along opposite sides thereof and having a discharging groove at opposite ends arranged in alinement, and an upstanding peg carried by the base board concentrically of the discharging grooves, said run-ways being provided with depressions.
4. A game apparatus comprising a base board having a plurality of run-ways along opposite sides thereof and having a discharging groove at opposite ends arranged in alinement, and an upstanding peg carried by the base board concentrically of the discharging grooves, said run-ways being pro-

vided with depressions of differing valua-
tions.

5. A game apparatus comprising a base board having a plurality of run-ways along opposite sides thereof and having a discharging groove at opposite ends arranged in alinement, an upstanding peg carried by the base board concentrically of the discharging grooves, and projectiles adapted to be discharged from within the grooves.

6. A game apparatus comprising a base board having a plurality of run-ways along opposite sides thereof and having a discharging groove at opposite ends arranged in alinement, an upstanding peg carried by the base board concentrically of the discharging grooves, projectiles adapted to be inserted within the grooves, and means for discharging the same therefrom.

7. A game apparatus comprising a base board having a plurality of run-ways along opposite sides thereof and having a discharging groove at opposite ends arranged in alinement, an upstanding peg carried by the base board concentrically of the discharging grooves, said run-ways being provided with depressions of differing valua-
tions, and projectiles of differing valuations adapted to be discharged from within the discharging grooves.

In testimony whereof I hereunto affix my signature in the presence of two witnesses.

EGBERT G. JACKSON.
